UNITED STATES PATENT OFFICE.

GEORGE W. PARKS, OF PROVIDENCE, RHODE ISLAND.

DESIGN FOR A CUFF-BUTTON.

SPECIFICATION forming part of Design No. 26,102, dated September 29, 1896.

Application filed June 11, 1896. Serial No. 595,220. Term of patent 7 years.

To all whom it may concern:

Be it known that I, GEORGE W. PARKS, a citizen of the United States, residing at Providence, in the county of Providence and State of Rhode Island, have invented and produced a new and original Design for Cuff-Buttons, of which the following is a specification, reference being had to the accompanying drawings, forming part thereof.

- 10. Figure 1 is a side view of my newly-designed cuff-button, showing the shoe on a line with the post, a position it occupies when the shoe is to be inserted into the buttonholes.
- 15. Fig. 2 is a side view at right angles to the view in Fig. 1, showing the shoe at right angles to the axis of the post. Fig. 3 is a view taken from the same side as Fig. 1, showing the shoe at right angles to the post. Fig. 4 is a plan view of the button; and Fig. 5 is a cross-section of the button, the thickness of the metal being shown in a solid black line.

The views are deemed necessary to clearly illustrate the design, because, the shoe being pivotally connected with the post, the button

may be viewed in either one of the positions 25 and in each presents to the eye a somewhat different appearance.

The leading feature of my design consists in the flat post having a spreading base extending from the button to the shoe, which 30 has an oval horizontal shape, a flat bottom, and convex top resembling a coffee-bean.

In the drawings, *a* indicates the button; *b*, the post, having the spreading base *c*, where it connects with the button. *d* is the bean-shaped shoe of the button.

Having thus described my newly-designed cuff-button, I claim as new and desire to secure by Letters Patent—

The design for a button herein shown and 40 described.

In witness whereof I have hereunto set my hand.

GEORGE W. PARKS.
